UNITED STATES PATENT OFFICE.

DAVID R. BROWN, OF PHILADELPHIA, PENNSYLVANIA, ASSIGNOR TO ROBERT M. GREEN,
FRANK D. GREEN, ROBERT M. GREEN, JR., LOUIS G. GREEN, AND EDGAR L. GREEN, OF
PHILADELPHIA, PENNSYLVANIA, A FIRM.

DESIGN FOR A JAR.

No. 39,291.

Specification for Design.

Patented May 5, 1908.

Application filed December 2, 1907. Serial No. 404,859. Term of patent 7 years.

To all whom it may concern:

Be it known that I, DAVID R. BROWN, a subject of the King of Great Britain and Ireland and the Isle of Man, and a resident of Philadelphia, Pennsylvania, have invented a certain new, original, and ornamental Design for a Jar, of which the following is a specification, reference being had to the accompanying drawing, forming part thereof,

in which is shown an elevation of the ornamental jar forming the subject of my invention.

I claim:

The ornamental design for a jar, as shown.
DAVID R. BROWN.
